BACKSTAND IDLER

George W. Johnson, Rockford, Ill., assignor to Fenlind Engineering Co., Loves Park, Ill., a corporation of Illinois

Application August 17, 1955, Serial No. 528,934

12 Claims. (Cl. 51—148)

This invention relates to a new and improved backstand idler for use with the endless belt used on grinding and polishing machines to keep the belt properly tensioned and running true at all times with minimum need of attention on the part of the operator once the necessary adjustments have been made.

The principal object of my invention is to provide a backstand idler of simpler and more economical construction providing improved belt tensioning and tracking adjustments for the idler pulley so that it is not necessary to have absolute center alignment between the idler pulley and the contact wheel and yet the abrasive belt can be kept running true with minimum need for attention on the part of the operator, and as a result better grinding can be done and greatly increased production is obtainable.

The invention is illustrated in the accompanying drawings, in which—

Fig. 1 is a perspective view of a grinder showing a backstand idler made in accordance with my invention, mounted on the floor behind it, although it will be understood that bench or wall mountings may also be used;

Fig. 2 is a plan view of the backstand idler with the abrasive belt removed, this device having a left-hand tilting adjustment, as distinguished from the right-hand tilting adjustment shown in Fig. 1;

Fig. 3 is a side view of Fig. 2;

Fig. 4 is a front end view on line 4—4 of Fig. 3, and Fig. 5 is an enlarged detail of a portion of Fig. 4.

The same reference numerals are applied to corresponding parts throughout the views.

Referring to the drawings, the reference numeral 5 designates a grinder or front stand having the contact wheel 6 detachably secured to the drive shaft 7 thereof to permit application of contact wheels of different diameters and widths, depending upon the grinding job to be performed with the endless abrasive belt. These belts also come in various widths, one of these coated abrasive belts being indicated at 8 running on wheel 6 and over an idler pulley 9 on the backstand idler, indicated generally by the reference numeral 10. An elongated crank 11 extends forwardly from the backstand idler to the operator's station at the grinder 5, and by manipulation of the handle 12 the tension in belt 8 may be increased or decreased as necessary. Another elongated crank 13 having an operating handle 14 on its front end is operable in similar manner from the operator's station at the front of the grinder to make the belt 8 run true by tilting adjustment of the pulley 9, and as previously indicated, the present invention is particularly concerned with improvements in the backstand idler concerned with the tension and tilting adjustments with a view to greater simplicity and economy of construction and avoiding one-side stretch of the abrasive belt and obtaining more even grinding under all conditions.

The backstand idler 10 comprises a supporting base consisting of front and rear brackets 15 and 16 in which parallel guide rods 17 are suitably fixedly mounted for slidable support of the idler pulley carriage 18. A coiled

2

compression spring 19 surrounds a shaft 20 mounted between the guide rods 17 for rotation in bearings 21 in frames 15 and 16 and held against endwise displacement by a collar 22 that is pinned to the forward end of the shaft, as indicated at 23. The shaft is threaded, as indicated at 24, and threads in a nut 25 that is held against rotation by slidable engagement with the bottom of a housing 26 in which the spring 19 is held caged between the nut 25 and the rear end wall of the housing, whereby normally to urge the housing 26 rearwardly and thereby, through the link connection indicated at 27 with the carriage 18, apply tension resiliently to the abrasive belt 8 running on idler pulley 9. A bell-crank lever 28 that is pivotally mounted, as at 29, on the carriage 18 and has pivotal connection, as indicated at 30, with the front end of the link 27 provides a means of quickly releasing the belt tension by moving the lever 28 in a clockwise direction about the pivot 29 so as to move the pivot 30 past deadcenter with respect to the pivot 29 and pivotal connection 31 of link 27 with the housing 26 and accordingly release the pressure of spring 19 on housing 26 and carriage 18 connected with it through link 27. The protruding front end portion of shaft 20 has one yoke of a universal joint 32 (Fig. 1) suitably secured thereto for rotary adjustment of the shaft 20 by means of crank 11 and handle 12 so that the tension on the belt 8 may be increased or decreased from the operator's position to a fine degree.

Tilting adjustment of the idler pulley 9 to obtain proper tracking of belt 8 is obtained by infinite adjustment of the length of the link connection 33 provided between the base plate 34, that is bolted to the carriage 18, as indicated at 35, and an arm 36 that extends forwardly from the vertical arm 37 of a bell-crank bracket 38, on which the arbor 39 for support of the idler pulley 9 is carried. The bracket 38 is adapted to be adjusted by this link connection to whatever minute angular degree may be necessary about its pivotal connection 40 with the base plate 34. The horizontally extending arm 41 of the bell-crank bracket 38 extends under the pulley 9 and slidably engages the back of the base plate 34 as an abutment, as clearly appears in Fig. 4, the pivot 40 being disposed in a vertical plane passing through the middle of the pulley 9. The link connection 33 comprises upper and lower sets of toggle links 42 and 43, respectively, the upper links 42 having a pivotal connection with the ends of a cross-bar 44, the enlarged middle portion 45 of which is received in an opening 46 in the outer end of the arm 36, while the lower links 43 are pivotally connected to the ends of another cross-bar 47, the enlarged middle portion 48 of which is received in a hole 49 provided in one end portion of the base plate 34, the left-hand end of this generally U-shaped base plate being used for a left-hand unit, like that shown in Figs. 2 to 4, whereas the right-hand end is used in the case of a right-hand unit like that shown in Fig. 1. The enlarged middle portions 45 and 48 of cross-bars 44 and 47, respectively, are spheroidal-shaped to provide the universal joint action required with the tilting adjustment of the bracket 38 with respect to the base plate 34. For the same reason, the washers provided at 50 and 51 between the links 42 and bearing 46 on the one hand, and between the links 43 and the bearing 49 on the other hand, are rubber washers for compressibility thereof to whatever degree may be necessary with different adjustments of the bracket 38, so that there need be no looseness in the pivotal connections, which might otherwise give rise to vibration and noise in the operation of the backstand idler.

These rubber washers also serve to seal the bearings 46 and 49 against entry of grit and dirt, so that easier operation and longer wear are assured. A collar 52 has a shaft 53 rotatable therein and this shaft is held against end-

wise movement by an annular shoulder 54 provided on the shaft and abutting one side of the collar, and a ring 55 that is pinned to the shaft and has abutment on the other side of the collar. The shaft 53 is threaded, as indicated at 56, and has a nut 57 threading thereon. Trunnions 58 on opposite sides of the collar 52 and trunnions 59 on opposite sides of the nut 57 provide pivotal connections for the inner ends of the links 42 and 43 with the collar 52 and nut 57. The opposite ends 60 and 61 of the shaft 53 are squared, the front end 60 having one yoke 62 of a universal joint attached thereto to provide connection with the crank 13, as shown in Fig. 1. When the shaft 53 is turned clockwise, nut 57 moves toward collar 52 to elongate the parallelogram defined by the toggle links 42-43 in a vertical direction, and the link connection 33 is accordingly increased in length, and vice versa when the parallelogram 42-43 is elongated in a horizontal direction. The adjustment in one direction (for lengthening link connection 33) is limited by engagement of nut 57 with collar 52, and in the other direction (for shortening link connection 33) by engagement of nut 57 with the front of the bracket 38. The shaft 53 extends through a slot 63 provided in the vertical arm 37 of the bracket 38 to provide operating clearance in a vertical direction for the shaft in the shortening and lengthening of the link connection 33.

It is believed the foregoing description conveys a good understanding of the objects and advantages of my invention. The appended claims have been drawn to cover all legitimate modifications and adaptations.

I claim:

1. In a grinding and polishing machine including a front stand having a motor driven contact wheel and a coated abrasive belt trained thereon, a backstand comprising a base, an idler pulley having said belt also trained thereon, an L-shaped bracket carrying a horizontal arbor on its vertical leg supporting said pulley, said bracket being pivotally mounted by its horizontal arm on said base on a substantially horizontal axis spaced laterally from said vertical leg and in a vertical plane passing through the middle of said pulley, and an adjustable length support for the bracket rigidly connecting the base and bracket in radially spaced relation to said pivotal axis to tilt the pulley relative to the vertical plane and hold it in tilted position.

2. In a grinding and polishing machine including a front stand having a motor driven contact wheel and a coated abrasive belt trained thereon, a backstand comprising a base, a carriage slideable back and forth on said base toward and away from the front stand, means for adjusting it away from the front stand for belt tensioning, an idler pulley mounted on said carriage and having said belt trained thereon, means defining an abutment transversely of said carriage, an L-shaped bracket carrying on its vertical leg a substantially horizontal arbor supporting said pulley, said bracket having its horizontal leg slidably engaging said abutment and pivoted relative thereto on a substantially horizontal axis spaced laterally from said vertical leg and in a vertical plane passing through the middle of said pulley, and a manually adjustable connection between said carriage and said bracket in radially spaced relation to said axis whereby said pulley is tiltable relative to the vertical plane and held in tilted position.

3. In a grinding and polishing machine including a front stand having a motor driven contact wheel and a coated abrasive belt trained thereon, a backstand comprising a base, an idler pulley having said belt also trained thereon, a bracket carrying an arbor supporting said pulley, said bracket being pivotally mounted on said base on a substantially horizontal axis in a vertical plane passing through the middle of said pulley, and an adjustable length support for said bracket rigidly connecting the base and bracket in radially spaced relation to said pivotal axis to tilt the pulley relative to the vertical plane and hold it in tilted position.

4. In a grinding and polishing machine including a front stand having a motor driven contact wheel and a coated abrasive belt trained thereon, a backstand comprising a base, an idler pulley having said belt also trained thereon, a bracket carrying an arbor supporting said pulley, said bracket being pivotally mounted on said base on a substantially horizontal axis in a vertical plane passing through the middle of said pulley, and an adjustable length support for said bracket rigidly connecting the base and bracket in radially spaced relation to said pivotal axis to tilt the pulley relative to the vertical plane, said adjustable length support comprising a toggle linkage defining a parallelogram structure extensible in a vertical direction for elongation of the support and extensible in a horizontal direction for shortening the support, two opposed corners of the structure being connected to the base and bracket, and manually adjustable means adjustably connecting the other two opposed corners of the structure.

5. In a grinding and polishing machine including a front stand having a motor driven contact wheel and a coated abrasive belt trained thereon, a backstand comprising a base, a carriage slideable back and forth on said base toward and away from the front stand, means for adjusting it away from the front stand for belt tensioning, an idler pulley mounted on said carriage and having said belt trained thereon, means defining an abutment transversely of said carriage, a bracket carrying an arbor supporting said pulley, said bracket slidably engaging said abutment and pivoted relative thereto on a substantially horizontal axis in a vertical plane passing through the middle of said pulley, and a manually adjustable connection between said carriage and said bracket in radially spaced relation to said axis whereby said pulley is tiltable relative to the vertical plane and held in tilted position.

6. In a grinding and polishing machine including a front stand having a motor driven contact wheel and a coated abrasive belt trained thereon, a backstand comprising a base, a carriage slideable back and forth on said base toward and away from the front stand, means for adjusting it away from the front stand for belt tensioning, an idler pulley mounted on said carriage and having said belt trained thereon, means defining an abutment transversely of said carriage, a bracket carrying an arbor supporting said pulley, said bracket slidably engaging said abutment and pivoted relative thereto on a substantially horizontal axis in a vertical plane passing through the middle of said pulley, and a manually adjustable connection between said carriage and said bracket in radially spaced relation to said axis whereby said pulley is tiltable relative to the vertical plane, said manually adjustable connection comprising a toggle linkage defining a parallelogram structure extensible in a vertical direction for elongation of the connection and extensible in a horizontal direction for shortening the connection, two opposed corners of the structure being connected to the carriage and bracket, and manually adjustable means adjustably connecting the other two opposed corners of the structure.

7. In a grinding and polishing machine including a front stand having a motor driven contact wheel and a coated abrasive belt trained thereon, a backstand comprising a base, an idler pulley having said belt also trained thereon, a carriage for said idler slideable back and forth on said base toward and away from the front stand, a rotatably adjustable screw carried on said base longitudinally thereof under said carriage having a nut threaded thereon and abutting one end of a compression spring that surrounds the screw, a housing through which the screw extends for rotation with respect thereto and in which the nut has slidable engagement with one wall thereof to prevent turning of the nut while the spring has abutment with another wall thereof to transmit the adjustable spring pressure to said housing, means at one end of said screw for rotatably adjusting the same to vary the spring pressure on said housing, a link pivotally con-

nected at one end to said housing, and a manually operable bell-crank lever pivotally mounted at one point on said carriage and pivotally connected at another point to the other end of said link, so as to permit moving the latter pivot from one side to the other of a dead-center with respect to the lever's pivot on the carriage and the link's pivot on the housing, whereby to apply tension to the belt or relieve the same of tension.

8. In a grinding and polishing machine including a front stand having a motor driven contact wheel and a coated abrasive belt trained thereon, a backstand comprising a base, an idler pulley having said belt also trained thereon, an L-shaped bracket carrying a horizontal arbor on its vertical leg supporting said pulley, said bracket being pivotally mounted by its horizontal arm on said base on a substantially horizontal axis spaced laterally from said vertical leg and in a vertical plane passing through the middle of said pulley, and an adjustable length support for the bracket rigidly connecting the base and bracket in radially spaced relation to said pivotal axis to tilt the pulley relative to the vertical plane and hold it in tilted position, said adjustable length support comprising a toggle linkage defining a parallelogram structure extensible in a vertical direction for elongation of the support and extensible in a horizontal direction for shortening the support, two opposed corners of the structure being connected to the base and bracket, and manually adjustable means adjustably connecting the other two opposed corners of the structure.

9. In a grinding and polishing machine including a front stand having a motor driven contact wheel and a coated abrasive belt trained thereon, a backstand comprising a base, a carriage slidable back and forth on said base toward and away from the front stand, means for adjusting it away from the front stand for belt tensioning, an idler pulley mounted on said carriage and having said belt trained thereon, means defining an abutment transversely of said carriage, an L-shaped bracket carrying on its vertical leg a substantially horizontal arbor supporting said pulley, said bracket having its horizontal leg slidably engaging said abutment and pivoted relative thereto on a substantially horizontal axis spaced laterally from said vertical leg and in a vertical plane passing through the middle of said pulley, and a manually adjustable connection between said carriage and said bracket in radially spaced relation to said axis whereby said pulley is tiltable relative to the vertical plane and held in tilted position, said manually adjustable connection comprising a toggle linkage defining a parallelogram structure extensible in a vertical direction for elongation of the connection and extensible in a horizontal direction for shortening the connection, two opposed corners of the structure being connected to the carriage and bracket, and manually adjustable means adjustably connecting the other two opposed corners of the structure.

10. In combination, a base, a pulley adapted to have a belt trained thereon, a bracket carrying an arbor supporting said pulley, said bracket being pivotally mounted

on said base on an axis in a plane passing through the middle of said pulley, and an adjustable length support for said bracket rigidly connecting the base and bracket in radially spaced relation to said pivotal axis to tilt the pulley relative to the aforesaid plane and hold it in tilted position, said adjustable length support comprising a toggle linkage defining a parallelogram structure extensible in one direction for elongation of the support and extensible in a direction at right angles to the first mentioned direction for shortening the support, two opposed corners of the structure being connected to the base and bracket, and manually adjustable means adjustably connecting the other two opposed corners of the structure.

11. In combination, a base, a carriage slidable back and forth on said base, a pulley mounted on said carriage and adapted to have a belt trained thereon, means defining an abutment transversely of said carriage, a bracket carrying an arbor supporting said pulley, said bracket slidably engaging said abutment and pivoted relative thereto on an axis in a plane passing through the middle of said pulley, and a manually adjustable connection between said carriage and said bracket in radially spaced relation to said axis whereby said pulley is tiltable relative to the aforesaid plane and held in tilted position, said manually adjustable connection comprising a toggle linkage defining a parallelogram structure extensible in one direction for elongation of the connection and extensible in a direction at right angles to the first mentioned direction for shortening the connection, two opposed corners of the structure being connected to the carriage and bracket, and manually adjustable means adjustably connecting the other two opposed corners of the structure.

12. In combination, a base, an L-shaped bracket having one leg of the L disposed substantially parallel to said base and pivotally connected thereto at its outer end, the other leg of the L being disposed substantially at right angles to said base, and a tilting adjustment for said bracket comprising an adjustable length support connecting the last mentioned leg of said L with said base in spaced relation to the aforesaid pivot, said adjustable length support comprising a toggle linkage defining a parallelogram structure extensible in one direction for elongation of the support and extensible in a direction at right angles to the first mentioned direction for shortening the support, two opposed corners of the structure being connected to the base and bracket, and manually adjustable means adjustably connecting the other two opposed corners of the structure.
